US00D615557S

(12) **United States Design Patent**
Mayer et al.

(10) **Patent No.:** **US D615,557 S**
(45) **Date of Patent:** **** May 11, 2010**

(54) **REWIND COVER FOR AN ENGINE**

(75) Inventors: **Bart Mayer**, Fond du Lac, WI (US);
John Sigrist, Greenfield, WI (US); **Carl Tiefenthaler**, Jackson, WI (US);
Michael Schultz, Menomonee Falls, WI (US)

(73) Assignee: **Briggs and Stratton Corporation**,
Wauwatosa, WI (US)

(**) Term: **14 Years**

(21) Appl. No.: **29/336,174**

(22) Filed: **Apr. 29, 2009**

CLAIM

We claim the ornamental design for a rewind cover for an engine, as shown and described.

DESCRIPTION

FIG. 1 is a perspective view of a rewind cover for an engine embodying the invention;

FIG. 2 is a top view of the rewind cover of FIG. 1;

FIG. 3 is a bottom view of the rewind cover of FIG. 1;

FIG. 4 is a first side view of the rewind cover of FIG. 1;

FIG. 5 is another side view opposite the first side view of the rewind cover of FIG. 1;

FIG. 6 is a front view of the rewind cover of FIG. 1; and,

FIG. 7 is a rear view of the rewind cover of FIG. 1.

The broken line portions are for illustrative purposes only and form no part of the claimed design.
